INVENTOR
Andrew Janer,
BY Leo J. McNally
ATTORNEY

UNITED STATES PATENT OFFICE.

ANDREW JANER, OF FLUSHING, NEW YORK.

PORTABLE PERFUMING DEVICE.

Application filed August 27, 1924. Serial No. 734,377.

To all whom it may concern:

Be it known that I, ANDREW JANER, a citizen of the United States, and a resident of Flushing, county of Queens, city and State of New York, have invented certain new and useful Improvements in Portable Perfuming Devices, of which the following is a specification, sufficient to enable those skilled in the art to which the invention

10 appertains to utilize the same.

My improvements relate to the type of device for containing and dispensing liquid perfumery by means of vehicular air impregnated therewith substantially as disclosed in my concurrent application Ser. No. 729,351, filed July 31st 1924, and likewise are designed to afford a simple, compact, but effective contrivance for the purpose designated, adapted to be carried on the person, and in which provision is made for regulating, during manipulation, the amount of perfume ejected in accordance with requirements, as well as for obviating waste, etc., as therein and hereinafter set forth,—the invention in the present case relating more particularly to the specific means provided for utilizing the full capacity of the liquid perfume reservoir, and for positively sealing the ejector nozzle when not required for use, whereby leakage may be effectually prevented irrespective of the positioning of the contrivance in inclination or reversed,—thus rendering my portable perfumer safe for transportation and use as an article to be disposed of in a vanity case, pocket, or otherwise as may be found most expedient or convenient for the user.

In the accompanying drawings I illustrate a practical embodiment of the essential features of my invention in concrete arrangement, although I do not limit myself to the identical form or construction of parts and appurtenances shown by way of exemplification, since changes may be made in minor details, and equivalent mechanical expedients resorted to, with like results, and without departing from the spirit and intent of my invention in this respect.

50 With this understanding:—

Fig. 1, represents an elevation of my portable perfuming device as retracted and closed;

Fig. 2, is a central longitudinal sectional elevation of the device when closed as in Fig. 1;

Fig. 3, is a central longitudinal section thereof as expanded for use;

Fig. 4, is a transverse section upon plane of line 4—4 Fig. 2;

Fig. 5, is a like section illustrating a change in the relative positions of the casing and the liquid container;

Fig. 6, is a sectional view taken upon plane of line 6—6 Fig. 2, illustrating the eccentric co-relation of casing and reservoir in effecting the sealing of the ejector nozzle.

The said figures of the drawings, for convenience of observation of structure and arrangement of parts, represent my perfuming device as of approximately double the size as actually manufactured for individual use, although the size is not material.

The upper end of the tubular casing C, is formed with a flange, the inturned annular edge c, of which is eccentric to the inner cylindrical surface of said casing. The lower extremity of said tubular casing C, is closed by a cap c', formed with a central orifice or perforation c², an annular washer c³, being preferably interposed between said cap c', and the adjacent edge of the tube C, as shown in Figs. 2 and 3, of the drawings.

The reservoir R, for containing the liquid perfume P, is of a diameter to fit snugly within the inturned eccentric annular flange c, of the casing C, and is closed at its lower extremity by a piston member r, rigidly attached thereto, and fitting snugly within the casing C, and also preferably provided with a cup-leather or equivalent packing r', to insure an airtight contactual engagement with the inner surface of the casing, especially during the depression of the reservoir as hereinafter set forth.

The coil spring S, is interposed between the piston member r, and the cap c', of the casing C, and tends constantly to press said piston member r, and reservoir R, outward into the position shown in Fig. 3, with the upper circumferential edge of the piston member r, resting against the aforesaid annular flange c, of the casing C, thereby limiting the outward thrust or movement of the reservoir R.

The eccentric annular flange c, of the casing C, is formed with a port notch or opening c⁴, for the accommodation of the protuberances e, which consists of the outer portion of the nozzle of the ejector tube e', which latter is positioned within the reser-

voir R, and extends at its other extremity approximately to the bottom of said reservoir. Adjacent to and extending above or beyond the ejector nozzle e, the ejector tube e', is bent into the form of a syphonic trap e², extending approximately to the upper air outer extremity of the reservoir R, so that practically the whole length and area of said reservoir may be utilized as a container for the liquid perfume, since the reservoir may be thus filled to a level with the under or concave side of said trap e², without overflow to the nozzle, this feature being a decided improvement over the form of ejector tube shown in my aforesaid concurrent application Serial No. 729,351, in which the syphonic trap e², is omitted, permitting an overflow to the nozzle e, if the liquid level extends above the latter.

Near the apex of its convex surface the syphon trap e², is formed with an inlet duct e³, communicating with the space thereabove in the reservoir, so that the forced discharge of liquid through the ejector pipe e', will induct air from the reservoir prior to its ejection through the nozzle, thereby the discharge and prevents the spraying of drops of liquid perfume through said nozzle and not only thus economizing the perfume but also obviates saturation of parts to be treated therewith.

An automatic-closing air inlet valve a, is mounted on the underside of the piston member r, of the reservoir R, the valve chamber of which communicates with an air inlet stand pipe a', extending approximately to the upper extremity of the reservoir R, as shown in Figs. 2 and 3, of the drawings, the upper end of said reservoir tube R, being closed by a cap K, which also functions as a finger rest for manipulative purposes. The cap K, is detachably connected to the tube R, to admit of the introduction of the liquid perfume P, into the reservoir R, and is preferably provided with a packing disc k, or equivalent means of effecting an air-tight joint between the parts when the said tube R, is closed.

When it is desired to retain the parts of the device in closed relationship, as in Figs. 1 and 2, of the drawings the protuberant portion of the nozzle e, on the reservoir R, is caused to enter the notch c^x, in the concentric annular flange c, of the casing C, and the reservoir is then partially turned on its longitudinal axis so as to bring said protuberant portion of the nozzle e, under said flange c, thereby locking the reservoir within the casing against the resistance of the expansion spring S, as shown more particularly in Fig. 2. Simultaneously with this interlocking of the parts, the partial rotating of the reservoir R, involved as just stated, owing to the eccentricity of the controlling flange c, seals the outer end of the

nozzle e, by reason of the contact therewith of the inner surface of the casing, the eccentricity of said flange c, as related to the inner cylindrical surface of the casing C, being such that a quarter turn, more or less, 70 of the reservoir R, on its longitudinal axis, or of the casing as related to the reservoir, is sufficient to seal the outlet of the nozzle, thereby preventing all possibility of leakage of liquid perfume irrespective of the position or inclination assumed by the device as thus closed upon itself, considered in a unitary sense. 75

In use, the device is grasped endwise between the thumb and finger, the parts being in the position shown in Fig. 3. If the air inlet c², on the otherwise closed extremity of the casing C, is covered, the depression of the reservoir R, against the resistance of the spring S, will cause the piston to force the air within the casing C, through the valve a, and tube a', into the reservoir R, and thence through the liquid perfume P,—the air thus impregnated with perfume being forced out through the ejector pipe e', and nozzle e.

Obviously if the air inlet c², is open during any portion of the inward thrust imparted to the reservoir R, the air in the casing C, will escape, in whole or in part, 95 through said inlet c², which thus becomes a means for regulating and varying the volume of impregnated air delivered to and through the nozzle e. Thus the quantity of perfume ejected may be governed with accuracy according to preference of requirements, and the possibility of waste is thus eliminated.

My perfuming device may be operated when held in any position; and furthermore, only impregnated air can be ejected, thus obviating waste of liquid, and staining or saturation of cloth, etc., which it may be desired to treat.

What I claim as my invention and desire to secure by Letters Patent, is:—

1. A portable atomizer comprising a casing, a reservoir for containing a liquid movably mounted in the casing, an exit nozzle on the reservoir for the discharge of the liquid, said nozzle projecting laterally from said reservoir at a point enabling said nozzle to be moved to a position within and to be concealed by the wall of the casing on the movement of said reservoir into said casing, said casing being provided with means to close the orifice in the nozzle when housed within said casing.

2. A portable atomizer comprising a casing provided with an air inlet at one end thereof, a reservoir for containing a liquid slidably and rotatably mounted in said casing, a nozzle projecting laterally from said reservoir at a point enabling said nozzle to be moved to a position within and to be con-

sealed by the wall of said casing on movement of said reservoir into said casing, in combination with means on said casing cooperating with the outer wall of the reservoir for causing the nozzle to engage with a part of the inner surface of the wall of said casing to prevent leakage.

3. A portable atomizer comprising a receptacle provided with an air inlet at one end thereof and with an inturned flange at the other end thereof having a notch therein and defining an opening which is eccentric with respect to said receptacle, a second receptacle for a liquid slidably and rotatably mounted in the first mentioned receptacle, and a laterally projecting exit nozzle mounted on said second receptacle and adapted to pass through said notch on movement of said second receptacle into said first receptacle, said flange and the walls of the receptacles cooperating with the nozzle to lock the two receptacles in fully telescoped relation and to positively seal the orifice in said nozzle upon relative rotation 25 of said receptacle.

4. A portable atomizer comprising a receptacle provided with an air inlet at one end thereof, a second receptacle for containing a liquid slidably and rotatably mounted in the other end of the first mentioned receptacle, an exit nozzle on the reservoir for the discharge of the liquid, said nozzle projecting laterally from said reservoir at a point enabling said nozzle to be moved to a position within and to be concealed by the wall of the first mentioned receptacle, said receptacles being provided with cooperating parts for positively sealing the orifice in said nozzle when one is housed in the other by a relative rotation of said receptacles.

5. A portable atomizer comprising a receptacle provided with an air inlet at one end thereof, a second receptacle for a suitable liquid adapted to reciprocate within the first mentioned receptacle, a laterally projecting exit nozzle on the second receptacle located at a point enabling said nozzle to be moved to a position within and to be concealed by the wall of the first mentioned receptacle, said receptacles being provided with cooperating parts for positively sealing the orifice in said nozzle by a relative movement of said receptacles.

6. A portable atomizer comprising a casing, a reservoir for containing a liquid slidably, rotatably and eccentrically mounted in said casing, a laterally projecting exit nozzle on the reservoir for the discharge of the liquid adapted to be moved to a position to be concealed within the wall of said casing, said nozzle being of sufficient length to contact with the inner surface of the wall of the casing as the nozzle is moved in a circumferential direction towards the narrowest point of the space defined by and existing between the casing and reservoir.

7. A portable atomizer comprising a compression receptacle, a second receptacle for containing a liquid slidably and rotatably mounted in one end of and telescoping with the first mentioned receptacle, a laterally projecting exit nozzle on the second receptacle for the discharge of the liquid adapted to be moved to a position to be concealed within the wall of the first mentioned receptacle, said receptacles being provided with cooperating parts which, when one receptacle is housed within the other, positively seal the orifice in the ejector nozzle upon a relative rotation of said receptacles.

ANDREW JANER.
